CLAIM

The ornamental design for a tent, as shown and described.

DESCRIPTION

FIG. 1 is a top, front and right side perspective view of a tent showing my new design;
FIG. 2 is a top plan view thereof;
FIG. 3 is a front elevational view thereof;
FIG. 4 is a bottom plan view thereof; and,
FIG. 5 is a rear elevational view thereof, the right side elevational view and the left side elevational view thereof being identical to that shown.

FIG. 1

FIG. 2

FIG. 3

FIG. 4

FIG. 5
